UNITED STATES PATENT OFFICE.

FLOYD M. BLAIN, OF CENTRAL POINT, OREGON.

BABY-JUMPER.

1,104,609.

Specification of Letters Patent. Patented July 21, 1914.

Application filed January 24, 1914. Serial No. 814,059.

To all whom it may concern:

Be it known that I, FLOYD M. BLAIN, residing at Central Point, in the county of Jackson and State of Oregon, have invented a new and Improved Baby-Jumper, of which the following is a specification.

This invention, which generally relates to appliances for supporting babies as they learn to walk, is more especially designed to serve as a combined baby jumper, a high-chair and a swinging cradle, the several parts being readily convertible to serve for either of the special purposes mentioned.

Generically, my invention has for its object to provide an appliance of the character stated, of a simple and economical construction, and in which the several parts can be almost instantly adjusted whereby to provide a baby jumper or walker, a swing, a high-chair, or a cradle swing, means being also included for yieldingly and adjustably sustaining the baby holding means from an overhead or ceiling support.

With other objects in view, that will hereinafter appear, my invention consists in the peculiar construction and novel arrangement of parts hereinafter fully explained, specifically pointed out in the appended claims and illustrated in the accompanying drawings, in which:

Figure 1, is a perspective view of my invention, the same being shown as a swing, the high-chair feature being included. Fig. 2, is a similar view, the same being shown as a baby walker or jumper. Fig. 3, is a similar view of my invention, the same being shown arranged as a cradle swing. Fig. 4, is a plan view of the baby holder or supporting body, parts being broken away to the better illustrate the construction of the said supporting body. Fig. 5, is a similar view of the yielding hanger portion of my complete invention, and Fig. 6, is a similar view of the overhead adjustable hanging devices. Fig. 7, is a perspective view of one corner of the body portion of my invention, parts being broken away to show the skeleton structure.

In its practical arrangement, my invention comprehends, as it were, three essential parts, an adjustable holder for suspending the complete appliance from a ceiling or other overhead support, a body or support by which the baby is sustained, and a yielding hanger that connects with the adjustable

holder and from which the baby sustaining body is flexibly suspended.

The suspension or holding elements, that form a part of my complete appliance, include a tubular bar 1, having a hook or eye 10 at the upper end for connecting with an eye or hook 2 on the ceiling, see Fig. 1. Within the bar 1 is slidably mounted a hanger rod 11 that is clamped at the desired positions in the bar 1 by the clamp screw 60 and lever 12. The lower end of the rod 11 terminates in an eye 13 for receiving a looped strap 3 having such buckle connections, whereby the said strap may be lengthened or shortened, at will, to suit the desired requirements.

The yielding hanger devices consist of a lower and an upper frame of like shape, but of considerable difference as to size, the upper frame being a plate approximately 75 square in plan view and having an opening 30 in each corner thereof. The lower or larger frame 5 has the shape of the frame 4 and is of a skeleton form, it being bent up from a single piece of stout wire rod, 80 and it is suspended from the frame 4 by coil spring hangers 6—6, the upper ends of which hook into the several openings 30 in the top frame 4, and the lower ends hook around the curved corner portions 40 of 85 the frame 5, and to hold the said lower ends of the spring hangers from creeping on the rod frame 5, spacing tubes 41 are mounted on the said rod frame between the lower ends of the spring hangers 6. 90

45 designate loops pendent from each of the corners 40 of the frame, the purpose of which will be presently explained.

The body or baby holding device, in my complete appliance, the construction of 95 which forms an essential feature of my invention, consists of a framing that includes a series of frame sections, each bent up from a stout wire member. One of the said sections, the central one, and herein-after termed the saddle section, has the shape of and is the same size of the hanger frame 5. To the saddle frame 7, are connected the opposite side sections 8—8, and the front and back frame sections 9—9, 100 each of which includes a metal rod bent to a U-shape and having the side arms 91, terminating in eyes 92 for hinging onto the side and end members of the saddle frame 7. The several frames 7, 8 and 9 are fur- 105 110

ther connected by a flexible covering, preferably stout canvas or ducking 15, which is doubled upon itself to completely cover the several frames 7, 8 and 9. At 5 the forward ends of the side frames 8, the flexible body 15 is formed with triangular shaped extensions 80—80, one of which has snap button fasteners 82, and the other fastener sockets 81 for coöperating with the 10 fasteners 82. Near the front end, the body portion 15, has a pair of leg openings 16 having reinforced edges 17, as shown.

18 designates flexible hangers, preferably chains, one for each corner of the frame 5, 15 the upper ends of which hook into the pendant loops 45. The lower ends of two of the hanger chains 18, at one side, connect to the outer edge of one of the side frames 8—8, and the opposite chains 18, connect with the 20 outer ends of the other side frame 8. Strap buckles 25 are secured to the under side of the outer edges of the side frames, and straps 26 are likewise secured to the under side of the end frames 9.

25 By reason of the peculiar construction and arrangement of the parts as hereinbefore described and as shown in the drawings, it is apparent that when the side and end members 8 and 9 are turned upwardly they 30 can be readily held secure to their upright position by the strap and buckle connection, it being also understood that the supplemental members or extensions 80 are bent in and preferably snapped 35 together before the front frame 9 is secured. When thus secured, the body portion of my appliance is arranged as a baby jumper or walker, since when thus adjusted the baby's legs extend through the saddle 40 frame openings, as understood by referring to Fig. 2.

When it is desired to use the appliance as a high-chair or swing, the baby is seated on the front edge of the saddle frame, with its 45 legs hanging over the turned-down front frame 8, the extensions or members 80—80 being at this time locked together, they serving as a guard for holding the baby from falling, it being apparent that when 50 thus adjusted the baby can freely move its hands through the front opening 27.

In some instances, particularly when the baby is old enough to stand, the members 80—80 may be opened and the baby with 55 its legs through the saddle frame can utilize the front frame 8 as a tray for food or play toys, as illustrated in dotted lines in Fig. 2.

When adjusted as shown in Fig. 3, my appliance forms a convenient cradle swing, 60 the front end 8 being suspended in a horizontal position, and the rear end 8, in a slightly inclined position by proper adjustment of the strap and buckle connections, and in this latter adjustment the extensions 65 80—80 are preferably joined, since they tend

to hold the baby's legs down and keep him from kicking or rolling off the cradle-like support.

From the foregoing, taken in connection with the drawings, the complete construction, the manner in which my invention may be adjusted and converted for use and its advantages will be readily apparent. 70

It will be noticed that since the saddle frame 7, the baby's frame 4 and the upper frame 3, are of like shape, the hanging connections are such that it is impossible for the saddle or cradle body to torsionally twist with respect to the over-head support, and the movements thereof will either be 80 regularly lateral or longitudinal and therefore danger of throwing the baby off the cradle support is reduced to the minimum. 75

What I claim is:

1. In a baby jumper, a baby holder consisting of a saddle portion, side and end sections hingedly connected to the saddle portion, said side sections including supplemental members or extensions, having interlocking means whereby when said sections 90 are joined they form a transverse guard, an overhead support, means for sustaining the baby holder, on the overhead support, and other means for holding the side and end sections to their relatively adjusted positions. 95

2. In a baby jumper, a baby holder comprising a central frame, formed of a wire strand bent to produce side and end portions; U-shaped frame sections hingedly connected to the side and end portions of the central frame, a flexible covering that incases all of the mentioned frames and is connected therewith, that portion of the flexible covering over the central frame having leg openings, means on the side and end sections for holding the said side and end sections locked to their adjusted positions, and a hanger connected to the opposite side frame sections for suspending the said 110 holder from an overhead support. 105

3. An appliance of the character described, in which is included a baby holder consisting of a central rigid frame composed of opposite side and opposite end portions, 115 side and end sections hingedly joined to the side and end portions of the central frame, a flexible body that covers all of the said frames, said body including triangular extensions adapted to overlap to form a transverse guard when the side members are adjusted to their swinging up position, means for holding the side and end frames to their adjusted positions, and means connected to the side frames for suspending the said 120 holder from an overhead support. 125

4. In a baby jumper, a seat or saddle portion, two side frames hingedly secured to said seat portion, over-head suspension means connected to said side frames, a cov- 130

ering over said side frames which includes flap members that are adapted to over-lap and form a front transverse guard, a front frame hinged to said seat portion, a back frame hinged to said seat portion, strap and buckle connections between said side frames and said front and back frames respectively,

and a cover over said front and back frames, substantially as shown and described.

FLOYD M. BLAIN.
